LOCK-SWITCH.

1,377,145.

Specification of Letters Patent.

Patented May 3, 1921.

Application filed January 17, 1916. Serial No. 72,392.

To all whom it may concern:

Be it known that we, STEPHEN F. BRIGGS and EDWARD N. JACOBI, citizens of the United States, and residents of Milwaukee, in the county of Milwaukee and State of Wisconsin, have invented new and useful Improvements in Lock-Switches, of which the following is a description, reference being had to the accompanying drawings, which are a part of this specification.

This invention has for its object to provide a lock switch for automobiles and the like, controlled by a key which is normally removed from the switch but which may be inserted and turned to lock or unlock the switch, the turning movements of the key causing longitudinal movements of a plunger to engage and disengage a locking means for a rotary switch member controlling the lighting circuits, and also serving to engage and disengage switch contacts for controlling the ignition circuit whereby the turning of the key in the lock to unlock the switch releases the switch member and permits it to be changed from one position to another and renders the ignition circuit operative, but the turning of the key in the lock to lock the switch prevents the change in position of the switch and renders the ignition circuit inoperative, thus preventing unauthorized use of the automobile or a tampering with the lights thereof.

Another object of the invention is to perfect details of construction whereby the switch, when locked, may not be unlocked except by the use of a proper key, and whereby the switch may be simplified in its construction to render it inexpensive to manufacture though efficient and durable in use.

With the above and other objects in view the invention consists in the lock switch as herein claimed and all equivalents.

Referring to the accompanying drawings, in which like characters of reference indicate the same parts in the different views,

Figure 1 is a front view of a lock switch constructed in accordance with this invention;

Fig. 2 is a rear view thereof;

Fig. 3 is a central sectional view thereof with the key removed and the switch locked;

Fig. 4 is a similar view thereof on a plane at right angles to the plane of Fig. 3, parts being broken away;

Fig. 5 is a sectional view similar to Fig. 3 with the key in place and the switch unlocked;

Fig. 6 is a rear view of the switch with the switch base removed and the switch member in the "off" position;

Fig. 7 is a similar view with the switch member in the "on" position;

Fig. 8 is a similar view with the switch member in the "dim" position;

Fig. 9 is a plan view of the switch base;

Fig. 10 is a bottom view of the switch member with the cam operated plunger in place;

Fig. 11 is a similar view thereof with the plunger removed;

Fig. 12 is a detail view of the key and its slide tumblers;

Fig. 13 is a bottom plan view of the switch handle;

Fig. 14 is a plan view of the plunger cam; and,

Fig. 15 is a perspective view of the spacer.

In these drawings 15 indicates a front plate in which is rotatably mounted a switch handle 16, preferably in the form of a turn button, as shown, to constitute a pointer indicating the position of the switch by being directed toward corresponding designations on the front plate. A cup-shaped casing 17 mounted on the back of the front plate is closed by an insulating switch base 18 which is secured in place by screws 19, and an insulating disk 20 within the casing is secured to the switch handle 16 by screws 21 so as to turn therewith, a stop lug 22 which projects from the edge of the casing 17 into an arc-shaped recess 23 of the insulating disk 20 serving to limit the movement of the switch handle by engaging the shoulders at the ends of said recess. The insulating disk 20 forms a switch member by having secured to it a metal switch spider 24, preferably in duplicate, with its radially extending spring arms bearing at their convex ends against the insulating base 18 and fitting in recesses or cavities 25 therein in the different positions of the switch. Some of the cavities 25 are formed in metal studs 26 which pass through the insulating base 18 and form binding posts on the rear thereof. One of the binding posts is adapted for connection with the battery, while the other binding posts have a resistance element 27 connected between

them and are adapted to be connected respectively to the rear lights and the headlights, and the arms of the switch spider 24 are so arranged that in the "off" position of 5 the switch no connection is made between the battery terminal and the others, but in the "dim" position connection is made between the battery terminal and the rear light terminal so that the taillight and headlights 10 will be lighted, but the headlights will be dimmed because of their circuit including the resistance element 27, and in the "on" position of the switch the battery terminal will be connected directly with the headlight 15 terminal as well as the rear light terminal, thus excluding the resistance from the headlight circuit and causing the headlights to burn brightly, as well as causing the taillight to be lighted.

20 Within a central bore of the switch handle 16 is rotatably mounted a shouldered, cylindrical lock barrel 28 through which passes a key slot 29 which is of a serrated shape in cross section to receive a correspondingly 25 shaped key 30. In a rectangular opening passing transversely through the lock barrel 28 are slidably mounted a series of thin flat sheet metal tumblers 31 with central openings irregularly positioned to correspond 30 with the irregular outline of the opposite edges of the key 30 when the key is in place in the lock, as shown in Fig. 12, thus being contained within the confines of the barrel 28 when properly positioned by the key so 35 that the lock barrel may be turned by the key. At diametrically opposite parts of the bore through the switch handle are recesses 32 into which the tumbler slides 31 may project in order that the key may be withdrawn, 40 and in one of these recesses is mounted a leaf spring 33 which bears on the tumbler slides to force them to project into the opposite recesses when the key is withdrawn, thus preventing the turning of the barrel 28. It 45 is obvious that barrel 28 can only be turned when the tumbler slides are moved to the relative positions shown in Fig. 12 and this may only be accomplished by inserting the key 30. When the key is in place, however, the 50 lock barrel 28 is free to be turned thereby though such turning movements are limited by a suitable stop so that the lock barrel is in position to have the key removed in either extreme of its turning movement. 55 This stop is formed by a lug 34 bent up from the edge of a cam plate 35 which is secured to the end of the lock barrel 28 by means of screws 36 and the stop lug 34 is adapted to engage shoulders 37 on the switch handle 16 to limit the movements of the lock barrel. 60 The cam plate 35 has a pair of arc-shaped tongues 38 cut from its opposite edges and bent downwardly therefrom to form helical cams, and a plunger member 39 which slidably fits within a central opening through 65 the insulating disk 20 has similar helical cams 40 secured thereto and engaging the helical cams 38 to cause a longitudinal movement of the plunger through the insulating disk 20 when the lock barrel is turned by the 70 key. The plunger is kept from turning by the presence of guide lugs 41 on the cams 40 which slide in guide grooves 42 in the switch handle 16. The helical cams 40 are formed in a disk-like stamping with its 75 edges cut to produce oppositely extending curved tongues spaced from a central portion 43, but united therewith at one end by radial arms 44, and resembling somewhat the shape of the letter S. In order to support the lock barrel 28 in a convenient manner a spacer is provided in the form of a sheet metal disk 45 with radial arms 46 bent down therefrom in the manner shown 80 in Fig. 15 and bearing on the insulating disk 85 20, said arms straddling the radial connecting arms 44 of cams 40 and passing through the spaces between said cams and the central portion 43 which is riveted to the plunger, as best seen in Fig. 10. The cam plate 35 90 rests on the top 45 of the spacer, as shown in Fig. 4, while the upper end of the plunger is free to rise within the spacer as shown in Fig. 3.

The lower end of the plunger 39 is provided with an insulating tip 47 to engage a spring locking member 48 which is secured to the switch base 18 by a pair of screws 49 and is preferably reinforced by a steel spring 50 also secured by said screws and 100 bearing against the bottom of the locking member. The outer end of the spring locking member 48 is preferably folded upon itself and soldered with its extremity bent downwardly to engage and move a spring 105 switch tongue 51 therebeneath when the locking member is depressed by the downward movement of the plunger 39. This folded end of the locking member is confined between the legs of a staple 52 embedded in 110 the insulating base 18, and in its upper position fits between or against either of a pair of locking pins 53 projecting downwardly from the bottom of the insulating disk 20. Thus, in any of the positions of the switch 115 handle the turning of the key in the lock to unlock the switch causes the helical cams 38 and 40 to coöperate with each other in forcing the plunger 30 downwardly to depress the locking member 48 out of the path 120 of travel of the locking pins 53 so that the switch handle is free to be turned as desired. Also, in any position of the switch handle the turning of the key in the lock to lock the switch causes the coöperation 125 of the helical cams 38 and 40 to permit the plunger 39 to rise under the pressure of the spring locking member 48 and thus engage the ends of the spring locking member with one or the other or both of the locking pins 130

53, as shown in Figs. 6, 7, and 8, to lock the switch handle against further movement.

The spring switch contact 51 is mounted on a metal stud 54 which passes through the 5 insulating base 18 and forms a binding post for connection with the magneto, and said contact spring, when relieved of the pressure from the locking member 48, springs upwardly into engagement with an over- 10 hanging contact 55 formed by cutting a notch in the side of another stud 56 passing through the insulating base and also forming a binding post for connection with a ground wire. Whenever the switch is un- 15 locked the plunger 39 is in its depressed position and consequently the spring contact 51 is held out of engagement with contact 55, as shown in Fig. 4, so that the magneto ignition circuit is effective for operating the engine, but whenever the switch is locked the plunger is in its raised position, shown in Fig. 3, and the spring contact 51 engaging the contact 55 maintains a ground 20 connection on the magneto which renders the ignition circuit ineffective and prevents the operation of the engine. Obviously the 25 connections with the binding posts 54 and 56 may be reversed or the contact 55 may be arranged to be engaged by the spring contact 51 only when the latter is depressed by the plunger, and thereby adapt the switch for use with battery ignition where the ignition switch is required to be closed to render the ignition circuit operative.

35 The switch of this invention is small and compact, and neat in its appearance, and still it is effective for the purpose intended and is strong and durable. The lock is of such a construction that it is impossible for 40 the switch to be tampered with either to render the ignition circuit operative in order to run the engine, or to change the connections for the lights.

What we claim as new and desire to secure by Letters Patent is:

45 1. In a lock switch, a rotary switch handle, a lock barrel rotatably mounted therein, tumblers carried by the lock barrel for engaging the switch handle to prevent the 50 turning of the lock barrel, a key fitting in the lock barrel to withdraw the tumblers from engagement with the switch handle to permit the lock barrel to be turned by means of the key, a locking member for preventing the turning of the switch handle moved into and out of its operative position by the turning of the lock barrel and a switch operated by the turning of the lock barrel.

55 2. A lock switch, comprising a switch handle, a lock for locking the switch handle in its different positions, a key for operating the lock and removable therefrom in either the locking or unlocking position of the lock and a switch operated by the lock.

60 3. A lock switch, comprising a switch

handle, a tumbler controlled lock barrel rotatably mounted therein, a cam operated locking means for locking the switch handle actuated by the turning of the lock barrel and a switch operated by the turning of 70 the lock barrel.

4. A lock switch, comprising a switch member having a handle, a rotatably mounted key controlled locking means in the handle, a cam actuated plunger moved by the 75 turning of the locking means, a locking member controlled by the movements of the plunger for locking the switch member and a switch operated by the movements of the plunger. 80

5. A lock switch, comprising a switch handle, a key controlled lock member rotatably mounted therein, a switch member carried by the switch handle, a plunger slidably mounted therethrough, a helical cam 85 on the lock member engaging the plunger for causing the plunger to slide through the switch member, and means for locking the switch member engaged by the plunger.

6. In a lock switch, a rotatably mounted switch handle, a key controlled lock member rotatably mounted therein, a switch member carried by the switch handle, a plunger slidably mounted through the switch member, co-operating helical cams on the plunger 90 and the locking member respectively for causing the plunger to slide when the locking member is turned, and means for locking the switch member engaged by the plunger. 95

7. A lock switch, comprising a switch handle, a key controlled lock member rotatably mounted therein, a switch member carried by the switch handle, a plunger slidably mounted therethrough, co-operating 100 helical cams on the plunger and the lock member respectively whereby the plunger is moved by the turning of the lock member, and a switch operated by the movements of the plunger. 105

8. A lock switch, comprising a switch handle, a lock barrel rotatably mounted therein, key controlled tumblers on the lock barrel for engaging the switch handle, a switch member carried by the switch handle, a plunger slidably mounted therein, a slotted spacer resting on the switch member and supporting the lock barrel, a helical cam on the lock barrel, a helical cam on the 110 plunger projecting through the slots of the spacer and engaging the helical cam of the lock barrel whereby the plunger is moved by the turning of the lock barrel, and a spring actuated locking member for locking the switch member engaged by the plunger. 115

9. A lock switch, comprising a casing, a switch handle rotatably mounted therein, a key controlled lock member in the switch handle, a switch member carried by the switch handle, a plunger passing there- 120

130

through, a helical cam connecting the lock member with the plunger for causing the plunger to be moved by the turning movements of the lock member, a switch base secured to the casing and having contacts engaged by the switch member, a spring actuated locking member on the switch base engaged by the plunger, and stops on the switch member engaged by the locking member for locking the switch against turning.

10. A lock switch, comprising a casing, a switch handle rotatably mounted thereon, a key controlled lock member in the switch handle, a switch member carried by the switch handle, a plunger slidably fitting in the switch member, means for sliding the plunger by the turning movements of the lock member, a switch base secured to the casing, and having contacts engaged by the switch member, a spring locking member mounted on the base and engaged by the plunger, a staple on the base confining the end of the spring locking member, and stops on the switch member adapted to be engaged by the spring locking member.

11. A lock switch, comprising a casing, a switch handle rotatably mounted thereon, a key controlled lock member in the switch handle, a switch member carried by the switch handle, a plunger slidably fitting in the switch member, means for sliding the plunger by the turning movements of the lock member, a switch base secured to the casing and having contacts engaged by the switch member, a spring locking member mounted on the base and engaged by the plunger, a stop on the switch member engaged by the spring locking member, a spring contact on the base engaged and moved by the spring locking member when

the latter is depressed, and a stationary contact engaged by the spring contact.

12. A lock switch comprising two switches, a lock for each switch, a removable handle for one switch, the attachment of the handle disabling the lock for said switch and the operation of said switch disabling the lock for the other switch.

13. The combination with a switch and its handle, of a supplementary switch, a removable handle therefor, and locking means controlled by the removable handle whereby the supplementary switch is unlocked and locked by the attachment and removal of the removable handle, and the other switch is locked and unlocked by the turning of the removable handle.

14. A lock switch mechanism including a removable key, one switch unlocked by inserting the key and operated by turning the key, another switch unlocked by turning the key, and a handle for operating said other switch.

15. A lock switch, comprising a switch and its handle, a member rotatably mounted on the handle and provided with a key opening, locking means for the switch operated by the turning of the member, a supplemental switch operated by the turning of the member, and key-controlled means for locking the member and the handle when the key is removed.

In testimony whereof, we affix our signatures, in presence of two witnesses.

STEPHEN F. BRIGGS.
EDWARD N. JACOBI.
